UNITED STATES PATENT OFFICE.

FRANK E. GETTS, DECEASED, LATE OF CHICAGO, ILLINOIS, BY EVA J. GETTS, ADMINISTRATRIX, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

BUS-BAR CLAMP.

1,380,550.

Specification of Letters Patent. Patented June 7, 1921.

Original application filed September 21, 1918, Serial No. 255,184. Divided and this application filed December 17, 1919. Serial No. 345,671.

To all whom it may concern:

Be it known that FRANK E. GETTS, late a citizen of the United States, residing at Chicago, in the county of Cook and State 5 of Illinois, deceased, has invented certain new and useful Improvements in Bus-Bar Clamps, of which the following is a full, clear, concise, and exact description, reference being had to the accompanying drawings, forming part of this specification.

The invention relates to bus-bar clamps, and particularly to that type of clamps which are designed to be mounted on an insulator, and which are adapted to securely 15 hold an electrical bus-bar conductor commonly of rectangular cross section, being relatively wide and thin.

It is a special object of the invention to provide an upright bus-bar clamp which is 20 so designed that it may hold from one to any number of bars without change of parts.

A further object also, is to provide such a clamp as may be securely mounted on an insulator, and which will clamp the bar or 25 bars in a central position relative to the axis of the insulator.

Other objects of the invention and invention itself will be better understood from the description thereof which follows, and 30 in which description, reference will be had to the accompanying drawings, in which there is illustrated one particular embodiment of the invention, and in which drawings:—

Figure 1, is a side elevational view of the 35 improved bus-bar clamp;

Fig. 2 is an end elevational view of the clamp illustrated in Fig. 1;

Fig. 3 is a plan view of the bus-bar clamp base member when the clamping 40 pieces illustrated in the other figures are removed.

Referring to the figures at 64, there is shown a bus-bar such as is commonly used in electric power stations. The bus bars 64 are 45 therefore made relatively thin, so as to offer to the air an extensive heat radiating surface so that the bus-bars will not overheat. Although in the figures only one bus-bar 64 is shown, it is to be understood that a plu-

rality of bus-bars 64, are used when the capacity of one bar is exceeded. A pair of clamping members 57—57 are provided, and are of triangular shape as herein shown, or of any other particular shape desired and are ribbed as shown at 58, to strengthen the 50 same. A flat base 52 has cast thereon an upstanding rib 53, which extends diagonally across the center of bars (53) and affords a supporting surface upon which the bus-bars 64 may rest. Bolting blocks 54—54 60 are formed integral with the base 52 and carry bolts 60 which project from the said bolting blocks 54—54 in both directions. These bolts comprise threaded rods or studs passed loosely through a hole in each of the 65 blocks 54—54 and in which blocks they are pinned as shown at 55, to prevent shifting. Separate bolts or studs may be fastened into the blocks 54, from each side.

Lugs 59—59 on the clamping members 70 57—57 have bolt holes through which bolt holes the bolts 60 are adapted to pass. The bolt 61, is passed loosely through similar bolt holes in the apices of the clamping members 57—57 and clamping nuts 62—63 and these 75 several bolts serve to draw the clamping members 57—57 into firm engagement with the bus-bar 64.

Although as has been said only one bus-bar 64, is illustrated in the drawings, the 80 clamp of the invention is so made that a considerable number of bus-bars 64, may be accommodated in the clamp if so desired, and the bolts 60—61 are therefore made sufficiently long to permit a wide separation of 85 the clamping members 57 for the accommodation of the desired number of bus-bars. These bolts 60—61 may be provided in various lengths for clamping different sizes or 90 numbers of bus-bars and other clamping members 57—57 may be substituted which are of greater or less height, when it is desired to accommodate bus-bars of corresponding widths.

It will be noted that the two clamping 95 members 57 are identical. These members are offset toward each other by substantially half of the thickness of the bolting blocks

54, so that they will hold the bar 64 centrally of the blocks 54. These clamps 57 are also arched over the central rib or web 53 to clear the same.

5 Although the clamp of the invention may be secured to any suitable base, it finds a very considerable use in practice when supported on the top of an insulator, preferably in the manner disclosed in the copending application, Serial No. 255,184, filed Sept. 21, 1918, of which application this is a division.

10 Cap screws 56 extend down through holes in the base 52 of the improved clamp into 15 the screw holes of a base member not herein illustrated, but which may preferably be provided on a clamp member adapted to be clamped on top of an insulator as illustrated in the above mentioned patent application. The rib 53 which extends across the center of the base 52 (Fig. 3) affords a supporting surface upon which a large number of bars 64, can be rested, the bars also thereby being incidentally kept in alignment. 20 25 The formation of the rib permits the cap screws 56 to be fastened centrally of the supporting base at the same time it is continuous transversely so far as its supporting function is concerned.

30 By making both of the clamping members 57, movable with respect to the base 52, a large number of bars 64, can be accommodated therebetween, and the bars 64 can be always disposed centrally, relative 35 to the supporting base to which the cap screws 56 are secured, when the clamp is thereby secured to the said base. This is particularly important when the bus-bars are carried on an insulator, since by the central distribution of the bus-bar weight, the 40 carrying insulator will not be unequally stressed, but the weight will be disposed centrally over the axis of the supporting base insulator.

45 It is not intended that the invention shall be limited to the particular details herein shown and described, except as defined in the appending claims.

What is claimed is:—

50 1. In combination, a bus-bar clamp, comprising a base portion said base portion having an upstanding ridge, and integrally formed with bolt carrying lugs disposed on either side of the said ridge, the upper surface of the said ridge being in a parallel plane with the plane of the bolts carried by the said lugs, each of the said bolts extending through the said lugs and having threaded portions on either side thereof, a 55 60 65 pair of clamping members adapted to be carried on the said bolts, one on each side of the said base portion the said clamping members having opposing parallel faces and clamping nuts on the ends of said bolts to secure the said clamping members.

2. In combination, a bus-bar clamp comprising a base portion, holding lugs extending from two opposite sides of said base portion, parallel bolts passing through the lugs an upstanding ridge for the said base portion, having an upper supporting surface parallel to the plane of the said bolts and adapted to support the weight of rectangular shaped bus-bars, a pair of opposing clamping members adapted to be carried on opposite sides of the said base portion on the said bolts, and clamping nuts carried by each of the said bolts to force the said clamping members together to securely clamp an interposed bus-bar. 70 75

3. In combination, a bus-bar clamp comprising a base-portion, bolting lugs extending from two opposite sides of said base portion, parallel bolts carried by the said lugs, an upstanding ridge for the said base portion having an upper supporting surface parallel to the plane of the said bolts and adapted to support the weight of rectangular shaped bus-bars, a pair of opposing clamping members adapted to be carried on opposite sides of the said base portion on the said bolts, and clamping nuts carried by each of the said bolts to force the said clamping members together to securely clamp an interposed bus-bar. 80 85

4. In combination, a bus-bar clamp, comprising a base portion, bolting lugs extending from said base portion, a pair of threaded studs passing through said lugs, said studs being pinned centrally in said lugs, a pair of opposing triangular shaped 105 clamping members guided on said studs, said pair of studs being adapted to pass through perforations in the said triangular shaped clamping members at two corners thereof, and a stud passing through aligned 110 perforations in the third corner of each of the said clamping members, said clamping members both being movable with respect to said base portion, clamping nuts for each end of the said studs, adapted to force the 115 said clamp members together to clamp an interposed bus-bar, the lower corners of the clamping members being set back to permit the clamping members to overhang the lugs.

5. In combination, a base, a pair of side 120 plates, a central transverse rib on the base and bolts securing said plates to the base below said rib, said plates being arched over said rib to clear the same.

6. In combination, a base, a pair of side 125 plates having two lower corners, a transverse rib on the central part of said base, said rib running diagonally across the center of the base, bolts securing said lower corners of the plates to the base below the level of 130

said rib, said plates being cut away to clear
said rib.

7. In combination, a base member having
a transverse supporting rib, bolts secured to
5 the base member below the top of the rib
and on each side thereof, and a side plate
adapted to lie on one side of the bars to be

clamped, said side plate being arched over
the rib and being held by said bolt.

In witness whereof, I hereunto subscribe 10
my name this 4th day of December, A. D.
1919.

EVA J. GETTS,
Administratrix for Frank E. Getts, deceased.
